(57) **CLAIM**

The ornamental design for a display screen or portion thereof with graphical user interface, as shown and described.

DESCRIPTION

FIG. 1 is a front view of a display screen or portion thereof with graphical user interface according to a first embodiment, showing my new design;

FIG. 2 is a front view thereof according to a second embodiment;

FIG. 3 is a front view thereof according to a third embodiment;

FIG. 4 is a front view thereof according to a fourth embodiment;

FIG. 5 is a front view thereof according to a fifth embodiment;

FIG. 6 is a front view thereof according to a sixth embodiment;

FIG. 7 is a front view thereof according to a seventh embodiment;

FIG. 8 is a front view thereof according to an eighth embodiment;

FIG. 9 is a front view thereof according to a ninth embodiment;

FIG. 10 is a front view thereof according to a tenth embodiment;

FIG. 11 is a front view thereof according to a eleventh embodiment; and,

FIG. 12 is a front view thereof according to a twelfth embodiment.

The outermost broken lines illustrate the display screen or portion thereof and form no part of the claimed design. The remainder of the broken lines illustrates portions of the graphical user interface that form no part of the claimed design.
